Patented July 30, 1968

211,790

CASING FOR AN ELECTRIC HEATER

John J. Murray, 10 Elsway Road,
Short Hills, N.J. 07078

Filed June 29, 1967, Ser. No. 7,640

Term of patent 14 years

(Cl. D23—113)

FIG. 1.

FIG. 2.

FIG.5.

FIG.6.

FIG.3.

FIG.4.

FIGURE 1 is a top plan view of a casing for an electric heater showing my new design partially broken away to indicate indefinite length;

FIGURE 2 is a front elevational view thereof;

FIGURE 3 is a bottom plan view thereof;

FIGURE 4 is a rear elevational view thereof;

FIGURE 5 is an end elevational view thereof, the opposite end being the same; and

FIGURE 6 is a cross-sectional view thereof.

I claim:

The ornamental design for a casing for an electric heater, as shown and described.
